UNITED STATES PATENT OFFICE.

GEORGE NORMAN, OF SMALL HEATH, NEAR BIRMINGHAM, ENGLAND, ASSIGNOR OF ONE-HALF TO THE BIRMINGHAM SMALL ARMS COMPANY LIMITED, OF SMALL HEATH, NEAR BIRMINGHAM, ENGLAND.

BACK-SIGHT FOR SMALL-ARMS.

No. 874,914.

Specification of Letters Patent.

Patented Dec. 24, 1907.

Application filed January 13, 1906. Serial No. 295,925.

To all whom it may concern:

Be it known that I, GEORGE NORMAN, a subject of the King of Great Britain, residing at 271 Charles road, Small Heath, near Birmingham, England, assistant engineer, have invented certain new and useful Improvements in Back-Sights for Small-Arms, of which the following is a specification.

This invention has relation to an improved 10 adjustable back sight, which is principally adapted for use in connection with miniature rifles and air-rifles, but is also applicable to other small arms.

The principal object of the invention is to 15 provide a simple but efficient combination back-sight in which the leaf is capable of an exact vertical adjustment for elevating and depressing the sight-bar to suit different ranges or distances, and also of an exact lateral adjustment to compensate for windage.

Figure 1 of the accompanying drawing represents a side elevation of a miniature rifle back-sight constructed in accordance with this invention and designed to admit of 20 the various adjustments above referred to. Fig. 2 is a longitudinal section of the said sight, and Fig. 3 is a plan of the same, with the fore part drawn in horizontal section to show the arrangement of the means provided 25 for effecting the lateral or wind-gage adjustment of the sight-bar. Fig. 4 is another view, similar to Fig. 3, but showing the laterally adjustable sight-bar and its adjusting screw detached from the leaf of the sight.

Fig. 5 represents the said separated parts in 30 side elevation: the head of the leaf being also shown in vertical section, and Fig. 6 shows the same parts in end elevation. Figs. 7 and 7^a represent two transverse vertical sec-

40 tions taken upon the dotted line x Fig. 1 and showing the adjustable sight bar in two different positions. Fig. 8 represents two detail sections taken respectively upon the dotted lines x¹ and x² Fig. 5.

45 The same letters of reference indicate corresponding parts in the several figures of the drawings.

In the improved sight represented in these 50 figures, the leaf a which carries a laterally-adjustable sight-bar b is adapted to be raised or elevated by a screw and nut adjustment c, d, in which the nut d, when rotated in one direction, is adapted to travel upon or ride along inclined ramps or bearings e arranged on

the opposite sides of a fixed bed f and so 55 part an upward angular movement to the leaf, while the lowering or depression movement is obtained by the action of a spring g when the adjusting nut is run back. By providing the rotative nut upon the stem 60 provision is made whereby liability of the shifting of the sight after adjustment through accident is reduced to a minimum. This is evident owing to the fact that the nut is practically self-locking and cannot be displaced 65 by a push or a blow, but only by a positive rotative movement. Thus, the bed or body of the sight is formed, at a short distance inwards of its rear end, with a pair of laterally separated ears or lugs f¹ between which is 70 jointed the stem a¹ of a leaf a adapted to have an angular movement in a vertical plane or to swing vertically from the said joint in the longer direction of the barrel upon which the sight is mounted, the said stem being guided 75 and steadied in its movement by forming its forward part a² with square or flat sides and arranging for same to fit closely and work between a pair of flat-faced guide pieces f² rising from the forward end of the bed and 80 coming behind the head of the leaf. The stem of the said leaf is wormed to form the screw c, and is provided with the milled or knurled adjusting nut d, which has at one end (preferably the forward end) a conoidal 85 bearing collar d¹ adapted to engage or seat itself upon the edges e¹ of a pair of inclined ramps or flanges e formed on the opposite sides of the bed and sloping gradually up- 90 wards from the rear end of the said bed to- 95 therof; the arrangement being such that when the nut is rotated in one direction, it advances upon the screw and its bearing collar rides along or traverses up the inclined planes with the result that the leaf is com- 100 pelled to make an upward angular move- 105 ment upon its joint and so gradually elevate the head end and notched sight bar which is mounted thereon, whereas by rotating the nut in the reverse direction, it runs down the screw and admits of the leaf head and sight bar being depressed by the action of a suitably applied spring such as g, which is also utilized to keep the elevating nut down against its bearing on the inclined ramps. This spring g is preferably secured in a space 110 between the ramps and is formed in such a

manner that its free end g^1 will exert an upward pressure against a tail or rearward extension a^4 of the leaf stem at a point beyond the joint lugs; thus the said spring has a constant tendency to depress the sight bar and to oppose the elevating action of the nut when the latter is being traversed up the inclines.

The sight-bar b is secured to the leaf-head 10 by a sliding dovetail connection, and the lateral or wind-gage adjustment of the said bar is obtained by a screw and nut adjustment in which the nut element is carried by the adjustable bar while the screw is swivelly-mounted in the head of the leaf but is confined against traversing movement so that its rotation in the one direction or the other will slide the sight bar either to the right or to the left, in addition to which the 20 said screw serves as the means for retaining the elements of the dovetail connection in engagement with one another. Thus the front edge of the head a^5 is formed with an open-fronted and open-ended dovetail groove 25 or channel h comprising an inner part h^1 (which may conveniently be of a circular section) and an open-fronted portion h^2 of less width than the part h^1 . The back edge of the sight-bar base is provided with a rib or 30 feather i of corresponding dovetail form, consisting of a barrel part i^1 adapted to have a sliding fit within the inner part h^1 of the channel h , and a flat shank i^2 which extends through the open-fronted part h^2 of the 35 groove and unites the sight bar to the barrel i^1 which is screwed internally and constitutes the nut of the adjustment. The swiveling adjusting screw j is directed along the inner part h^1 of the groove so as to engage with the 40 nut of the sliding sight bar, while to prevent its lateral displacement without affecting its swiveling or rotatory movement in both directions and also to facilitate the fitting of the sight-bar to the leaf in assembling the 45 parts of the sight, the shank of the said screw carries a collar j^1 which normally engages with and is free to swivel within an open fronted recess j^2 cut in the front of the leaf head at right angles to the groove h . 50 The sight-bar is assembled to the head by first passing the screw through the front of the groove h and engaging the collar j^1 with the recess j^2 so that the head of the said screw will abut against the left hand end of 55 the leaf-head, after which, the dovetail-like rib of the sight bar is introduced into the right hand end of the said groove h so as to present the barrel nut to the screw, when by rotating the latter, the threads of the screw 60 and nut are engaged and the sight bar is drawn into its assigned position, and when thus engaged, the mutual connection exist-

ing between the collared screw, the dovetail-sectioned nut of the sight bar and the grooved leaf head prevents the sight bar from being withdrawn lengthwise from the end of the said groove and also prevents the screw from being lifted through the open front thereof without affecting the lateral adjustability of the sight bar.

The movable parts of the sight are provided with a system of vernier scales or graduations to facilitate the various adjustments. For instance, the edge of one of the ramps may be marked with graduations 75 spaced apart to distances corresponding to one rotation of the elevating nut, while the bearing collar of the said nut is marked with other graduations, which, when used in conjunction with the marks on the ramp admit 80 of a very fine and exact elevation or depression adjustment being readily obtained. The sliding sight bar is also marked with a series of close graduations which are used in conjunction with a single mark or index 85 at the center of the leaf head and thereby facilitates the exact or delicate lateral adjustment of the said bar for windage. The head of the wind-gage screw may also be graduated for facilitating the fine lateral adjustment of the sight-bar.

Having fully described our invention, what we desire to claim and secure by Letters Patent is:—

1. In a back sight for fire arms, the combination with the sight bar having a hinged screw stem, of a nut rotatable upon and traversing the said stem, and inclined ramps carried on the bed of the sight and upon which the said nut rides for obtaining elevation adjustment.

2. In a back sight for fire arms, the combination with the sight bar having a hinged screw stem, of a nut rotatable upon and traversing the said stem, inclined ramps carried on the bed of the sight and upon which the said nut rides for obtaining elevation adjustment, and a spring permanently influencing the hinged stem and adapted to act upon the same at a point beyond its center so as to oppose the upward angular movement which the said stem is constrained to make by the traversing of the adjusting nut along the ramps, thereby holding the sight absolutely steady in all 115 positions.

In testimony whereof I have hereunto set my hand in presence of two subscribing witnesses.

GEORGE NORMAN.
